UNITED STATES PATENT OFFICE.

DAVID GENESE, OF BALTIMORE, MARYLAND, ASSIGNOR, BY DIRECT AND MESNE ASSIGNMENTS, TO THE GENESE COMPRESSOR AND MOULDING MACHINE COMPANY OF BALTIMORE CITY, OF MARYLAND.

SUPPOSITORY AND METHOD OF MAKING SAME.

SPECIFICATION forming part of Letters Patent No. 553,907, dated February 4, 1896.

Application filed May 23, 1895. Serial No. 550,444. (No specimens.)

To all whom it may concern:

Be it known that I, DAVID GENESE, a citizen of the United States, residing at Baltimore city, in the State of Maryland, have invented new and useful Improvements in Protecting-Integuments for Suppositories, &c., of which the following is a specification.

This invention relates to suppositories and analogous articles, composed in whole or in part of medicinal ingredients, which, when molded or shaped into a definite form, are very difficult to handle or transport, and are exceedingly liable to lose their original form or shape, and be seriously damaged if unprotected or exposed at any or all points to the action of the atmosphere.

The chief object of my present invention is to provide a suppository or analogous article with a new and improved external covering or protecting medium which possesses such characteristic features that it effectually and perfectly excludes the atmosphere, retains the inclosed article in its original molded form, and is susceptible of being conveniently and swiftly removed entirely from the suppository or analogous article whenever the latter is to be applied to the purpose for which it is designed. This object is accomplished in the manner and by the means hereinafter described and claimed.

In order to enable my invention to be clearly understood, I have in the accompanying drawings illustrated, in addition to the suppository itself, a series of molds for shaping the suppositories, a former for imparting to the sections of the integument a definite shape corresponding to the form of the article which is to be inclosed thereby, and a die for uniting the rims of the integument-sections together and compressing the folded edges of such rims.

In the accompanying drawings, illustrating my invention, Figure 1 is a perspective view of a suppository inclosed within a protecting-integument according to my invention. Fig. 2 is a transverse sectional view of the same. Fig. 3 is a detail perspective view showing the two similar sections prior to their application to the suppository. Fig. 3^a is a

detail view of a cap or end piece for covering the exposed end of the suppository. Fig. 4 is a detail perspective view of separable mold-sections in which the suppositories are molded into the desired form and inclosed in the integuments, a pair of the integument-sections being shown in position in the parts of one mold-cavity. Fig. 5 is a detail perspective view of the two parts or sections of a forming device for imparting a form or shape to the integument-sections corresponding to the form or shape of the molded suppository. Fig. 6 is a detail perspective view of the die-sections for uniting the rims of the integument-sections and compressing the folded edges of such rims. Fig. 7 is a sectional view of the die-sections, showing how the rims of the integument-sections are united and their edges turned laterally. Fig. 8 is a similar view showing how the folded edges of the rims are compressed to make air-tight joints, and Fig. 9 is a detail longitudinal sectional view showing how one end of the inclosing integument can be made of sufficient length to be folded over and thus close such end.

In order to enable those skilled in the art to practice my invention, I will now describe the same in detail, referring to the drawings, wherein—

The numerals 1 and 2 indicate two similar sections having an outline substantially the same as the outline of the suppository or analogous article which is to be covered and protected.

The sections 1 and 2 are preferably composed of tin-foil, but they may be made of starch-paper or any other material suitable for the purpose in hand, and which has no special affinity for or will not too closely adhere to the suppository or analogous article when the latter is inclosed between the sections composing the integument.

The tin-foil or other protecting-sections are formed with continuous laterally-projecting rims 3 and 4, which may be of any suitable width, but in actual practice are one-fourth of an inch in width, more or less. The sections are each formed or shaped into approxi-

mately the form or shape of the suppository or analogous article to be covered and protected. This is readily accomplished through the medium of a former, which is illustrated 5 in Fig. 5. This former comprises sections 5 and 6. The section 5 is constructed with a cavity 7, corresponding exactly, or approximately, with the form or shape of the suppository which is to be covered or protected.

10 The section 6 is constructed with a projecting former 8, of a shape which will accurately fit into the cavity 7. The sections composing the integument are formed by placing suitable pieces of tin-foil or starch-paper over 15 the cavity in the former-section 6, and then placing the two former-sections together and causing the former 8 of the section 6 to press the tin-foil or starch-paper down into the cavity 7 in such manner as to leave the edge 20 of each piece of tin-foil or starch-paper extending laterally to form the continuous rims corresponding to the rims 3 and 4, hereinbefore mentioned.

25 The molded or shaped sections of tin-foil or starch-paper are then placed in the mold-cavities 9 of the separable mold-sections 10, and after the latter are tightly clamped together the hot fluid, or semifluid material from which the suppositories are to be produced, is introduced into the mold-cavities between the sections of tin-foil or starch-paper.

30 The introduction of the material in a hot condition into the tin-foil integument secures an air-tight adjustment of the suppository material, and is very important for the preservation of the suppository.

35 The apparatus for heating the material and introducing the same into the molds is preferably such as is described and shown in my application for Letters Patent filed of even 40 date herewith, Serial No. 550,445.

45 When the suppositories are properly shaped by the separable mold-sections, the latter are opened and the suppositories covered with the tin-foil or starch-paper are carefully removed and laid one at a time into the cavity 12 of a lower die-section 13, which cavity is of a form corresponding to the form of the suppository.

50 The wall of the cavity 12 is formed with a horizontal top edge 14 to receive and support the laterally-projecting rim, which extends continuously in a longitudinal direction entirely around the suppository. The other die-block section 15 is then pressed upon the 55 die-section 13, which section 15 contains a cavity 16, similar in shape to the cavity 12, and is constructed with a continuous shoulder 17 and rim 18, both having a shape corresponding approximately to the shape of the 60 incased suppository. The shoulder 17 co-operates with the flat top edge 14 of the die-section 13 to compress the laterally-projecting rims of the tin-foil or starch-paper sections tightly together, so that they are securely 65 united. The rim 18 presses the outer edge of the united tin-foil or starch-paper rims upon the outer surfaces of the die-block sections 13

around the horizontal or flat edge 14, after which the die-sections are separated, the suppository is reversed in position in the die-section 70 13, the edge of the rim is folded over, and the die-section 15 is again operated, so that the folded outer edge 3^a of the tin-foil or paper-rim is tightly compressed for the purpose of hermetically sealing the joint or seam, and 75 rendering it impossible for the atmosphere to gain access to the inclosed suppository.

80 The folding of the edge of the rim of the inclosing integument is a very desirable and important feature, in that it provides a hermetically-sealed joint which effectually excludes the atmosphere. The laterally-projecting rim constitutes in one sense a finger-piece which affords ample means for conveniently and swiftly tearing off the tin-foil covering or protecting-integument whenever the 85 suppository or analogous article is to be applied to the purpose for which it is designed. The tin-foil or equivalent material will not unduly adhere or stick to the material of which 90 the suppository or analogous article is composed, and the rim provides such a projecting part that the entire covering can be very quickly and entirely removed without liability of damaging the suppository in any 95 manner.

95 The rim is a very advantageous element, in that it provides for the swift removal of the integument, which is very important when it is considered that the suppository itself is 100 very susceptible to heat, and if retained in the fingers an undue length of time in removing the covering, the suppository is likely to melt or lose its original molded form or shape.

105 The exposed extremity of the suppository or analogous article lying between the integument-sections 1 and 2 may be covered and protected by stearine-paper, paraffine, or any other material, or it may be covered with a tin-foil or starch-paper cap-piece 19, which is 110 clearly shown in Fig. 3^a. This cap-piece can be molded or shaped into the desired form, and the semicylindrical portions 20 will fit over the end portion of the covered suppository, while the lateral lips 21 can be folded 115 around the rim of the protecting-integument.

120 In Fig. 9 the two sections 1 and 2, composing the inclosing integument, are of such length that when applied as hereinbefore explained the integument extends to such extent that it can be folded over upon itself, as clearly indicated by dotted lines, for the purpose of closing one end of the integument air-tight.

125 It will be observed from the foregoing that it is proposed to close one end of the integument either by covering the exposed end of the suppository with starch-paper or paraffine or by applying thereto a tin-foil or other cap-piece 19, Fig. 3^a, or by making the integument-sections of such length that one end of the integument can be folded over upon itself, as in Fig. 9.

130 I do not wish to be understood as confining

myself to any particular means for closing the end of the integument into which the material composing the suppository is introduced.

A protecting covering or integument possessing the characteristics described is easily removable, it prevents the article deteriorating in efficacy or becoming contaminated, it preserves the form or shape of the article, and in the molding operation the integument-sections prevent any and all parts of the suppository from adhering or sticking to the surfaces of the metal or other mold.

Having thus described my invention, what I claim is—

15 1. The method herein described of making suppositories, which consists in reducing a medicament to a fluid condition by heat, lining a mold with sections of insoluble material, such as tin-foil, introducing the hot 20 medicament into the mold between the sections of the insoluble material, subsequently

compressing the insoluble material longitudinally along the opposite edges and around one end of the suppository, and applying a protecting substance to the other end of the suppository, substantially as and for the purposes set forth. 25

2. A suppository having an inclosing, insoluble, air-tight integument, such as tin-foil, composed of two similar molded sections provided with continuous, laterally-projecting rims united together and folded at the outer edge to hermetically seal them and effectually exclude moisture, substantially as described. 30

In testimony whereof I have hereunto set 35 my hand in presence of two subscribing witnesses.

DAVID GENESE.
